BELT AND CONTROL ASSEMBLY FOR
ARTIFICIAL LIMBS

Frederick J. Perrin, Prophetstown, Ill.

Application November 20, 1940, Serial No. 366,461

3 Claims.

(Cl. 3-2)

This invention relates to an artificial limb support and control means, and more particularly to a belt and control means for artificial legs for amputations above the knee.

It is an object of this invention to provide a belt and control means for an artificial leg whereby in the belt does not interfere with the breathing or in any manner inconvenience the wearer.

It is another object to provide a belt means of elastic material which is capable of expanding and contracting with the motion of the body of the wearer so that the belt means remains in its correct position at all times.

It is another object of this invention to provide a belt assembly and control means for an artificial limb whereby the artificial limb is firmly held to the body without causing the belt to sag or become disarranged regardless of the position assumed by the wearer thereof.

It is a further object of this invention to provide a belt and control assembly for an artificial leg so that the artificial leg will be firmly held to the body in any position assumed by the wearer. That is, the wearer of this belt and control assembly for an artificial leg can step, sit, kneel, crawl and the like and the artificial leg will be held firmly to the body or stump of the leg, and as a result there is no pinching and chafing of the stump of the leg.

It is a still further object of this invention to provide a belt and control assembly for an artificial limb whereby the toe of the foot of the artificial limb is maintained in a straight, correct position for safe and comfortable walking.

It is a further object of this invention to provide a belt and control assembly for an artificial leg for an amputation above the knee whereby the safest and most comfortable service is obtained, affording the wearer thereof entire freedom and still serves all of the functions for which it is designed, such as sitting, lying, stooping, kneeling, and the like. After being employed in the positions of sitting, lying, stooping, and the like, it is not necessary to adjust the artificial leg on the stump of a leg by twisting, pulling and the like, when an upright position is resumed.

Other objects and advantages of the invention will hereinafter be made fully apparent in the specification and pointed out in the claims.

In the accompanying drawings, which illustrate the invention, like characters indicate like parts throughout the several views.

Referring to the drawings:

Figure 1 is a front view of a person having

an artificial leg, wearing the belt and control assembly therefor, and showing the front of the belt and control assembly.

Figure 2 is a rear view of a person having an artificial leg, and showing the rear view of the belt and control assembly as mounted on the wearer.

Figure 3 is a top plan view, on an enlarged scale, of the belt and control assembly for an artificial leg.

Figure 4 is a sectional view taken on line 4-4 of Figure 3.

Figure 5 is a fragmentary view of an artificial limb, showing control means mounted thereon.

Figure 6 is a fragmentary view of the front control strap mounted on a spring steel member of the belt.

Referring in detail to the drawings: 10 indicates a person with an amputation above the knee, and the person is shown with the artificial limb in position on the stump of the amputated leg 14. The belt and control assembly for the artificial limb 12, is indicated by the numeral 16.

20 A belt 18 is adapted to be worn about the waist of the person having the amputated leg and is for aiding in supporting and holding said artificial limb 12 in position on the leg stump 14. The belt 18 is made of elastic material, and the belt 18 being of elastic material adjusts itself to the body of the wearer and permits entire freedom for breathing and for movements of the body in assuming different postures. The belt 18 is reinforced throughout its length by vertically spaced stays 15 which prevent rolling and sagging thereof. Buckle and strap means 17 are employed for securing the ends of the belt together. A length of leather 20 is stitched or otherwise secured longitudinally of the belt 18 and extends from near the front opening 19 of the belt to about $\frac{3}{4}$ of the distance around the belt, and the length of leather 20 forms a pocket or runway 22 for carrying a length of spring steel approximately $\frac{3}{8}$ of an inch wide and $\frac{3}{16}$ of an inch thick and which is about 24 inches in length. The length of spring steel is encased in a leather shield 24. The piece of spring steel 23 is spaced edgewise or flat against the belt in the runway 22 of the length of leather 20.

25 One end of the length of leather 20 is closed, as at 25 while the opposite end 26 is open. The length of leather 20 has spaced cut-out portions 28, and connecting parts 30, between the sections 32 thereof, which are not stitched to the belt 18, and as a consequence the belt can expand and

contract with movements of the body, or the material forming the runway for the spring steel may be made of elastic material and being stitched at intervals to belt 18 so that the belt can stretch with body expansion or when other strains are applied thereto. The piece of spring steel 23 spaced in the runway 22 of the length of leather 20, slips freely therein as the belt 18 expands and contracts through the motions of the body.

An adjustable leather strap 34 is looped to the length of spring steel 23 at the front portion of the belt 18 and depends downwardly over the center of the leg stump 14. The center arm 36 of a strap assembly 42 is detachably secured to the strap member 34 through a buckle 44 and loop means 45. The other arms of the strap assembly 42 are designated 38 and 40 respectively. Each of the arms of the strap assembly 42 is made of elastic material. The lower ends of the arms 36, 38 and 40 of the strap assembly 42 are joined together by a leather covering 44. A buckle 46 attached to the leather covering 44 is adapted to fasten the strap assembly 42 to a strap 48. Arms 38 and 40 of the strap assembly 42 have their upper ends secured to the upper portion of the artificial leg 12, while arm 36 is not attached to the artificial leg but is threaded through a half ring member 50 which is fastened to the artificial leg.

The strap 48 extends through an aperture 51 in the front portion of the artificial leg and runs over a roller means 52 inside the artificial leg, thence out an aperture 54 in the rear of the artificial leg. The strap 48 extends to and is connected to an elastic strap 56, and the elastic strap 56 is adjustably secured to the steel spring means 23 carried by belt 18, slightly back of the hip of the wearer.

A strap means 58 is looped to the steel spring means 23 of the belt 18 at the hip of the wearer 10 and extends downwardly to the upper part of the thigh of the artificial limb 12 and is secured thereto at 60. The strap 58 comprises an elastic portion 62 and a non-elastic portion 64. A 45 half inch in width strap 57 is connected to the elastic portion 62 of the strap assembly 58 and extends across the front of the thigh, being secured by a buckle means 59 to the inner front side of the artificial limb 12 at the crotch of the wearer. Strap 57 holds the top of the artificial limb firmly in the crotch. The buckle means 59 permits adjustments of the strap 57.

The half ring 50 holds the strap 34 and arm 36 of the strap assembly 42 in a straight line 55 and insures that the strap 48 will transmit a straight pull through arm 36 and strap 34 on the spring steel member 23 of the belt 18. The belt 18 is adapted to carry a part of the weight of the artificial limb 12 in walking through means of strap 34 which is attached to the steel spring means 23 of the belt 18 at the front portion thereof, elastic arm 36 of the strap assembly 42, strap 48 which passes over a roller means 52 in the artificial leg, and the elastic strap member 56 which is secured to the steel spring member 23 of the belt 18 slightly to the rear of the hip. This combination of straps is adapted to hold the artificial limb firmly to the stump of the amputated leg, when the wearer is in an upright position. The arm 36 of the strap assembly 42 being of elastic material imparts a springy action to the artificial limb.

When the artificial limb 12 is lifted in walking, the arms 38 and 40 of the strap assembly 75

42 will stretch as they assume the strain of the artificial limb at the front portion thereof. As the strain of the artificial limb 12 increases on the arms 38 and 40 during the process of taking 5 a step, they will gradually stretch. The gradual stretching of the arms 38 and 40 as the artificial limb is raised furnishes a springy resistance, the strain coming on the limb itself in the front at the points where arms 38 and 40 are secured to 10 the artificial leg, and on the belt 18 at the rear through the means of straps 48 and 56. When the strain of the artificial limb 12 is on the arms 38 and 40 of the strap assembly 42 and on the rear of the belt 18, through the medium of straps 15 48 and 56, the arm 36, strap 34 and straps 51 and 58 are relaxed. Further, arm 36 aids in holding the artificial limb 12 against the stump of the leg when in an upright or standing position, while the arms 38 and 40 aid in holding the artificial limb against the stump of the leg 14 when the knee of the artificial leg is bent in walking or in positions other than upright. The arms 38 and 40 of the strap assembly 42 also function to hold said limb to the stump of the leg during the acts of sitting, kneeling, and crawling. There are no metal connections between the belt 18 and the artificial limb 12, and therefore the artificial limb 12 has a free side action, when the limbs are spread apart. The arm 36 aids in holding the artificial limb to the stump of the leg, as the said limb returns to the straight position at the completion of a step. Also the angular position of the arms 38 and 40 in relation to the thigh and their juncture with each other, holds the toe of the foot of the artificial limb 12 in the correct position for safe and comfortable walking, thus lessening the dangers of stumbling or falling, and making it possible to clear rough walks or other obstacles.

The straps 34, 56, and 58 being looped to the spring metal supporting member 23 of the belt 18 so that they pull down on the top edge of the said spring metal supporting member when the artificial leg is being used, and with such mountings, an even pull is placed on the belt and therefore much weight can be sustained by the belt 18, and the belt will still maintain its proper position on the waist of the wearer. The strap 58 which is partially elastic, assists in carrying the weight of the artificial limb 12, helps in holding the said limb in its proper position and furnishes an adjustment at the hip, allowing free side action to the limb and at the same time holding the side of the artificial limb's socket firmly to the stump of the leg 14. Suspenders (not shown) may be used to maintain the belt 18 in position upon rising from a chair or other postures and as a consequence the belt need not be worn as tightly as otherwise.

What is claimed as new is:

1. A control assembly for an artificial leg comprising a flexible belt adapted to be applied around a body at the waist of a wearer, a supporting member carried by the belt, a strap secured to said supporting member, a flexible strap assembly comprising three arms, the strap extending to the central arm of the flexible strap assembly, a juncture formed at the lower end of the strap assembly, the upper end of two of the arms of the strap assembly being fastened to the artificial leg, a second strap extending from the juncture of the strap assembly and passing through apertures in the artificial leg and extending to the rear of the belt and being secured to the supporting member of the belt.

2. A control assembly for an artificial leg for an amputation above the knee comprising an elastic belt adapted to be applied around a body at the waist of a wearer, a pocket member secured to the belt, a spring metal supporting member being carried flat against the belt in the pocket member, the spring metal supporting member being free to expand and contract with the belt, a strap secured to the spring metal supporting member, a flexible strap assembly comprising three arms spaced at the thigh portion of the artificial leg, the strap extending to and being connected to the flexible strap assembly, the upper end of two arms of the strap assembly being fastened to the artificial leg, a 15 second strap extending from the strap assembly through apertures in the artificial leg and extending to the rear of said belt and being secured to the spring metal supporting member thereof, and a third strap member secured to 20 the spring metal supporting member of the belt at the hip of the wearer and extending to the artificial leg at the side thereof and being fastened thereto.

3. A control assembly in combination with an artificial limb for an amputation above the knee comprising a belt adapted to be applied around a body at the waist of a wearer, a strap secured 5 to the belt, a flexible strap assembly comprising three arms spaced at the thigh portion of the artificial limb, the strap extending to and being connected to the strap assembly, the upper end of two arms of the strap assembly being fastened to the artificial limb, a second strap extending from the strap assembly through the artificial limb and extending to the rear of said belt and being secured thereto, a third strap member secured to the belt at the hip of the wearer and extending to the artificial limb at the side thereof and being secured thereto, and a fourth strap means connected to the said third strap member, and the fourth strap means extending to the upper inside of the artificial limb and being secured thereto.

FREDERICK J. PERRIN.
